UNITED STATES PATENT OFFICE

159,070

COMBINED ELECTRIC SHAVER AND HEAD GUARD

Ivar Jepson, Oak Park, Ill., assignor to Sunbeam Corporation, Chicago, Ill., a corporation of Illinois

Application November 29, 1946, Serial No. 135,155

Term of patent 14 years

(Cl. D22—3)

To all whom it may concern:

Be it known that I, Ivar Jepson, a citizen of the United States, residing at Oak Park, in the county of Cook and State of Illinois, have invented a new, original, and ornamental Design for a Combined Electric Shaver and Head Guard, of which the following is a specification, reference being had to the accompanying drawing, forming part thereof.

In the drawing:

I claim:

The ornamental design for a combined electric shaver and head guard, substantially as shown.

IVAR JEPSON.
